CLAIM

We claim the ornamental design for a video camera display, as shown and described.

DESCRIPTION

FIG. 1 is a top front perspective view of a first embodiment of a video camera display of the present invention in an open position;

FIG. 2 is a front view thereof;

FIG. 3 is a rear view thereof;

FIG. 4 is a top view thereof;

FIG. 5 is a bottom view thereof;

FIG. 6 is a first side view thereof;

FIG. 7 is a second side view thereof;

FIG. 8 is a top rear perspective view thereof;

FIG. 9 is a top rear perspective view of a video camera display of the present invention in a closed position;

FIG. 10 is the video camera display shown in FIG. 1 without showing the environmental structure;

FIG. 11 is a second embodiment of the video camera display of the present invention;

FIG. 12 is a third embodiment of the video camera display of the present invention; and,

FIG. 13 is a fourth embodiment of the video camera display of the present invention.

The ornamental design which is claimed is shown in solid lines in the drawings. The broken lines showing the environmental structure in FIGS. 1-9 are for illustrative purposes only and form no part of the claimed design.
